CLAIM

The ornamental design for a beverage bottle with football surface ornamentation, as shown and described.

DESCRIPTION

FIG. 1 is a front elevational view of a beverage bottle with football surface ornamentation showing my new design;

FIG. 2 is a rear elevational view thereof;

FIG. 3 is a left elevational view thereof;

FIG. 4 is a right elevational view thereof;

FIG. 5 is a top plan view thereof;

FIG. 6 is a bottom plan view thereof;

FIG. 7 is a front elevational view of an alternate embodiment of FIG. 1;

FIG. 8 is a rear view of the embodiment of FIG. 7;

FIG. 9 is a left view of the embodiment of FIG. 7;

FIG. 10 is a right view of the embodiment of FIG. 7;

FIG. 11 is a top plan view of the embodiment of FIG. 7; and, FIG. 12 is a bottom plan view of the embodiment of FIG. 7. The broken lines are for illustrative purposes only and form no part of the claimed design.
